UNITED STATES PATENT OFFICE

149,744

DESIGN FOR A COMBINED DENTAL OPERATING LAMP AND SUPPORT

Ernest H. Greppin and John A. Salvia, Rochester, N. Y., assignors to Wilmot Castle Company, Rochester, N. Y., a corporation of New York

Application July 27, 1946, Serial No. 132,026

Term of patent 14 years

(Cl. D48—20)

To all whom it may concern:

Be it known that we, Ernest H. Greppin and John A. Salvia, both citizens of the United States of America and residents of Rochester, in the county of Monroe and State of New York, have invented a new, original, and ornamental Design for a Combined Dental Operating Lamp and Support, of which the following is a specification, reference being had to the accompanying drawings, forming part thereof.

Fig. 1 is a side elevational view of a combined dental operating lamp and support, showing our new design;

Fig. 2 is a top plan view thereof; and

Fig. 3 is a front elevational view thereof.

The characteristic features of the design reside in the portions shown in full lines.

We claim:

The ornamental design for a combined dental operating lamp and support, substantially as shown and described.

ERNEST H. GREPPIN.
JOHN A. SALVIA.
